UNITED STATES PATENT OFFICE.

ANTHONY B. CLARK, OF OELWEIN, IOWA.

STEAM-CHEST FOR STEAM-ENGINES.

1,178,574.

Specification of Letters Patent. Patented Apr. 11, 1916.

Application filed June 7, 1915. Serial No. 32,529.

To all whom it may concern:

Be it known that I, ANTHONY B. CLARK, a citizen of the United States, and resident of Oelwein, in the county of Fayette and State of Iowa, have invented certain new and useful Improvements in Steam-Chests for Steam-Engines, of which the following is a description, reference being had to the accompanying drawings, which form a part of my specification.

My invention relates to a steam-chest, which is illustrated as especially adapted to the use of an inside admission piston-valve for the distribution of steam, of simple and effective construction and which may be readily applied to steam engine cylinders previously provided with the ordinary type of slide valves.

One object of my invention is to provide a steam-chest preferably comprising a single or one piece casting, either of cast iron or cast steel, adapted to be secured to the flat valve surface of the cylinder in any convenient manner, as, for example, by studs, so as to permit the steam or valve-chest to be readily detachable.

Another object of my invention is to provide a steam or valve-chest which may be adapted to the use of any construction of inside admission piston-valve, and wherein the steam passages or ports are arranged to register with the steam passages or ports of cylinders, adapted for the operation of ordinary slide-valves; the passages for the exhaust steam being arranged to extend from the ends of the steam-chest about the sides thereof, and preferably full length of the chest intermediate of the live steam passage and the outer wall of the chest, so as to provide an insulation for the live steam passage in the chest; the passage being so arranged, however, as to connect with the exhaust port of a flat slide-valve type of cylinder.

Another object of my invention is to provide a construction adapted to the use of a piston-valve wherein the wear of the valve and valve-seats will be greatly obviated; the pressure due to frictional resistance, encountered in the slide-valve cylinder type reduced; and at the same time providing a construction wherein the packing of the valve is removed beyond the action of the live steam.

Furthermore, my invention enables the use of larger steam-ports than is possible or

practicable with the slide-valve type, without, however, placing unnecessary strain upon the valve-gear; the construction presenting an unusually free opening on the 60 exhaust side with the result that back pressure in the cylinder is materially reduced; and, furthermore, the construction permits of a better distribution of lubricant.

In the drawings:—Figure 1 is a vertical 65 central sectional view through the steam or valve-chest and adjoining portion of a steam engine cylinder, illustrating the application of my invention. Fig. 2 is a front elevation of a portion of a locomotive with the front- 70 head of the smoke-box removed, illustrating the application of my improved steam-chest. Fig. 3 is a longitudinal sectional plan view of my improved steam-chest with the valve and valve-bushings removed; the view being 75 taken on line 3—3 of Fig. 4, looking in the direction of the arrows. Fig. 4 is a transverse sectional view, taken on the line 4—4 of Fig. 3, looking in the direction of the arrows. Fig. 5 is a transverse view taken 80 on the line 5—5 of Fig. 3.

In the particular exemplification of my invention, as illustrated in the drawings, the invention is shown applied to the cylinder 10 which is provided with the usual flat 85 valve-face previously intended for the operation of the ordinary flat slide-valve; the invention, as illustrated, disclosing what is known as an inside admission piston-valve which is especially adapted for use in connection with a locomotive employing superheated steam. The steam is conveyed to the steam-chest by means of steam-pipe 11, shown located inside of the smoke-box 12, and connected with the steam-chest 13 by 90 means of the outside connection 14, see Fig. 2, instead of employing the live steam passages 10, 10^a extending through the saddle casting 15 and cylinder 10, and which are employed in connection with the ordinary 100 slide-valve type of cylinder.

The steam-chest 13 preferably consists of a single or one piece casting, made either of cast iron or cast steel, and adapted to be secured to the flat valve-face of the cylinder 105 10 by means of the studs 16, see Figs. 1 and 2.

The cylinder, as illustrated in Fig. 1, is shown provided with the transverse induction and eduction passages or ports 17, 17 110 and the intermediate exhaust passage or port 18. The ports or passages 17, 17 of the

cylinder communicate with the ports or passages 17^a, 17^b of the steam-chest, while the passage or port 18 in the cylinder communicates with the central port or passages 18^a of the steam-chest, as shown in Fig. 1.

The inner wall of the steam-chest, which constitutes the valve-chamber 19, see Fig. 3, is provided adjacent the ends thereof with the circumferentially extending channels 20, 20 which form continuations of the passages or ports 17^a. The valve-chamber of the steam-chest is provided with the cylindrical bushings 21, 21 arranged on opposite sides of the vertical center of the steam-chest, and are provided with bridged ports 22, 22 registering with the ports or channels 20, 20 in the wall of the valve-chamber.

The steam-chest 18 is shown provided with a central inlet port 23, see Figs. 1, 2 and 5, whereby the live steam is admitted centrally to the valve-chamber of the chest. The valve-chamber, in the particular exemplification illustrated, is provided with a piston-valve comprising the longitudinal barrel or cylinder-portion 24, of smaller diameter than the inside diameter of the valve-chamber of the chest, so as to provide the steam-space 24^a circumferentially about the valve. The ends of the barrel or cylinder 24 are flared, as shown in Fig. 1, and provided with the annular parallelly extending flanges or tongues 25 arranged intermediate of the inner and outer periphery of the barrel or cylinder so as to provide shoulders on both sides of the flanges or tongues 25. The shoulders adjacent the inner circumference of the cylinder 24, and at both ends thereof, are adapted to receive the peripheral portions of the spider-heads 26, 26. The heads 26, 26 are secured to the valve-stem 27 in a usual manner to firmly engage the ends of the cylinder or barrel 24. The heads 26, 26, in conjunction with the ends of the barrel or cylinder 24, are arranged to receive the reduced inner circumference of the bull-rings 28, 28, as shown in Fig. 1; the heads 26, 26 being off-set or shouldered so as to present a surface similar to the ends of the cylinder 24. The outer circumference of rings 28, 28 are of a width sufficient to completely cover the bridged ports 22, 22 in the bushings 21, 21, thus closing off communication between the central portion of the valve-chamber,—surrounding the barrel or cylinder 24,—and the cylindrical channels 20, 20 when the valve is in a central position, and, therefore, effecting communication with the passages or ports 17^a, 17^b; the valve in Fig. 1 being shown in a central position, where-
60 by both ports or passages, for the live steam, are covered and flow to the cylinder prevented. The ends of the steam-chest are closed by suitable heads 29 and 30 which may be secured in place in any suitable manner, as, for example, by stud-bolts. The

rear steam-chest head 30 is provided with the hub-portion 31, adapted for the passage of the piston-valve rod 27, and to receive the usual packing, as shown at 32 in Fig. 1.

The inner circumference of the valve-chamber portion of the steam-chest is preferably shouldered, as shown at 33, to receive the flanged or shouldered ends of the bushings 21, 21, as shown in Fig. 1, thereby determining the extent to which the bushings may be inserted into the steam-chest to bring the respective ports into register; the ends of the bushings being preferably bevelled, as shown in Fig. 1.

The longitudinal or side walls of the valve or steam-chest are provided with chambers or passages 34, 34, see Figs. 3, 4 and 5, which substantially surround the wall of the valve-chamber, extending from both ends of the steam or valve-chest toward the center, where they unite, and extend downwardly so as to terminate in the central port or passage 18^a which registers with the exhaust port 18 of the cylinder; the port 18, as usual, leads through the saddle-casting and discharges into the atmosphere in the usual manner by means of exhaust nozzle 35. As shown in Fig. 3, both ends 36, 36 of the steam-chest are in communication with the central port or passage 18^a, and by reason of the hollow valve construction, both ends of the chest are in communication with each other, so that exhaust steam, entering either end of the chest, may pass into the adjacent passage 34, as well as through the valve to the opposite end of the chest, and thence into the communicating passage 34.

At points coincident with the steam-passages or channels 20, 20, I provide the steam-chest with peep or sight-holes 37, 37, whereby the position of the valve may be observed; the holes 37, 37 being closed by suitable threaded plugs, not shown.

The chest is also provided with lubricating openings or holes 38, 38, arranged preferably adjacent the inlet passage or port 23, as shown in Fig. 1, so that the lubricant will come into contact with the outer surfaces or peripheries of the bull-rings 28, 28, during reciprocation of the valve.

In the exemplification of my invention as disclosed in the drawings, the live steam passes, from the boiler by means of steam-pipe 11, port 23, into the steam space or chamber 24^a surrounding piston-valve 24, intermediate of the ends thereof. Reciprocation of valve 24, toward the right in Fig. 1, will cause the bridged ports 22, in the bushing 21 at the right, to be uncovered, so that the steam may pass into channel 20 at the right-hand end of the chest, from whence it will pass through port 17^a into induction port 17 of the cylinder and be discharged at the right-hand end of the cylinder. Movement of the valve 24, as described, will an-

cover the ports 22 in bushing 21 at the left of the chest, thereby establishing communication with the ports 17^a and 17 at the left-hand end of both the chest and the cylinder, respectively. This will permit the exhaust steam to pass upward through ports 17, 17^a, channel 20 and out through the ports 22 of the bushing into the left-hand end 36 of the steam-chest. The exhaust steam then 10 passes from the end 36 into the circumferential passages 34 in the wall of the steam-chest, flowing toward the center of the chest and thence into the port 18^a which communicates with port 18, from whence the 15 exhaust steam passes into the atmosphere in the usual manner.

Reversing the stroke of the piston-valve, will, of course, cause steam to be admitted at the left-hand end of the cylinder and exhaust to enter the steam-chest at the right-hand end.

By reason of the construction shown and described, the exhaust steam substantially surrounds or incases the live steam space or 25 chamber in the steam-chest, and provides insulation therefor, whereby condensation of the live steam will be greatly reduced.

As is evident from the construction shown and described, the valve-rod packing 32 is 30 also removed from the live steam pressure, so that a much more efficient steam-chest is provided.

As is apparent from the construction, my improved steam-chest, having the exhaust steam passages and ports arranged as described, permits of its adaptation to locomotives equipped with the ordinary slide-valve cylinders without the necessity of replacing said cylinders with cylinders of the piston-40 valve type, thus enabling the locomotive to be changed from one employing saturated steam, controlled by ordinary slide-valves, to a superheated steam-type employing inside admission piston-valves.

45 My improved construction also enables the use of much larger steam-ports than would be practicable with the slide-valve construction, without, however, placing unnecessary strain upon the valve-gear. Furthermore, with my improved construction, comparatively large and free openings are provided on the exhaust side of the valve, with the consequent result that back pressure in the cylinder is materially reduced.

55 The construction, herein shown and described, also enables a better distribution of lubrication, so that wear of the valve and its seats will not only be materially overcome, but the loss of pressure, due to frictional resistance, reduced.

I have shown and described what I believe to be the best form of my invention, wherein the steam is admitted to the steam-chest by means of the connection or port 23; 60 but it is apparent that the steam-chamber

24^a could be supplied in a different manner, and other details of construction might be altered without, however, departing from the spirit of my invention as set forth in the appended claims, and I do not wish to be understood, therefore, as limiting myself to the exact construction shown and described.

What I claim is:—

1. As an article of manufacture, a steam-chest comprising an integral casting having induction and eduction ports and an intermediate port arranged to register with similar ports of a slide-valve type of cylinder, said casting being adapted to receive an inside admission type of piston-valve, said casting being also provided with steam-passages connected with the ends of the casting and extending longitudinally in the side walls thereof and communicating with said intermediate port.

2. As an article of manufacture, a steam-chest comprising an integral casting adapted to receive a piston-valve and provided with steam passages or ports in the bottom wall thereof adapted to register with the ports of a slide-valve type of cylinder, and having steam passages extending longitudinally in the side walls of the casting intermediate of the inner and outer surfaces thereof and terminating in a single downwardly presented exhaust port.

3. A steam-chest comprising an integral casting adapted to receive a piston-valve and provided with a flat lower flanged surface, the lower surface being provided with a pair of induction and eduction ports and an intermediate exhaust port arranged to register with the ports of a slide-valve type of cylinder, said casting being provided with an inlet port, and with exhaust steam passages extending longitudinally in the side walls of the casting and communicating centrally with the exhaust port in the lower surface of the casting.

4. A steam-chest for steam engines, comprising an integral casting having a flat lower surface adapted to be secured to the flat ported surface of a flat slide valve type of cylinder, said lower surface being provided with a pair of induction and eduction ports and an intermediate exhaust port arranged to register with the ports of the cylinder, said casting being provided with an inlet port arranged intermediate of its ends, and with passages extending longitudinally in the side walls of the casting, communicating with the casting interior at the ends thereof, said longitudinal passages terminating in a single downwardly presented passage communicating with the exhaust port.

5. A steam-chest for steam engines, comprising an integral casting having an inlet passage intermediate of its ends, and a pair of induction and eduction ports and an in-

termidate exhaust port in the lower surface of the casting adapted to register with the ports of a slide-valve type of cylinder, the side walls of the casting being provided with longitudinally disposed passages having communication with the interior of the casting at the ends thereof and terminating in a single downwardly presented passage communicating with the exhaust port in the lower surface of the casting, in combination with an inside admission piston valve comprising a hollow cylinder adapted to confine the live steam centrally in the casting while the exhaust steam has free passage through the valve from end to end in the casting.

6. A steam-chest for locomotives and the like, provided with an intermediate steam-inlet, induction and eduction ports or passages arranged on opposite sides of said steam-inlet and terminating in a flat-faced bottom adapted to register with the flat valve face of a slide-valve type cylinder, and exhaust passages extending from the ends of the chest and terminating at the bottom in an intermediate exhaust port registering with the exhaust port of a slide-valve type cylinder.

7. A steam-chest for locomotives and the like, provided with an intermediate steam-inlet, induction and eduction passages arranged on both sides of said inlet and intermediate of the ends, a piston-valve whereby the live steam is confined centrally within said chest, and exhaust passages extending from the ends of the chest and terminating in an intermediate port, the induction and eduction ports and said intermediate port being arranged to register with corresponding ports of a slide-valve type cylinder.

8. A steam chest for locomotives and the like, provided with an intermediate steam-inlet, induction and eduction passages or ports arranged on opposite sides of said inlet and intermediate of the ends of the chest, said induction and eduction passages or ports terminating at the bottom of the chest, and exhaust passages extending from the ends of the chest through the side walls thereof and terminating at the bottom in a single intermediate exhaust port.

9. A steam-chest for locomotives and the like, provided with a flat bottom surface adapted to be secured to the flat valve surface of a slide-valve type cylinder, said chest being provided with a steam-inlet at a point intermediate of the ends of the chest, a piston valve whereby the live steam is confined centrally within the chest, induction and eduction ports arranged on opposite sides of said steam-inlet and terminating in the bottom of the chest at points coincident with the induction and eduction ports of a slide-valve type cylinder, and exhaust passages arranged at both ends of the

chest and terminating in the bottom at a point intermediate of the induction and eduction ports so as to register with the exhaust passage of the cylinder.

10. A steam-chest for locomotives and the like, provided with an intermediate steam-inlet, an induction and eduction port arranged on each side of said inlet steam and intermediate of the ends of the chest, bushings arranged on each side of said steam-inlet and provided with bridged ports registering with the induction and eduction ports of the chest, an inside admission piston valve for confining the live steam centrally within the chest, and exhaust passages extending substantially throughout the length of the chest and communicating with the ends of the valve-chamber thereof, said exhaust passages terminating in a single central exhaust port, the ports of the chest being arranged to register with corresponding ports of a slide-valve type cylinder.

11. A steam-chest for locomotives and the like, provided with a central steam-inlet, a circumferential channel arranged on each side of said steam-inlet and terminating at the bottom in induction and eduction ports, bushings provided with ports arranged on opposite sides of said inlet and across said circumferential channels, exhaust passages arranged in the side walls of the chest leading from the ends thereof and terminating centrally in a single exhaust-port, said ports being arranged to register with the ports of a slide-valve type cylinder, and means whereby lubricant is admitted at the steam-inlet ends of said bushings.

12. A steam-chest for locomotives and the like, comprising a casting provided with a valve-chamber extending longitudinally therethrough, a steam-inlet communicating with the valve-chamber at a central point, induction and eduction steam-channels arranged on both sides of said steam-inlet and terminating at the bottom of said casting, and exhaust passages arranged in the side walls of the steam-chest and communicating with the ends of the valve-chamber, said exhaust passages being curved downwardly at a point intermediate the ends of the chest and terminating in the bottom of said casting in a single exhaust port arranged intermediate of the induction and eduction ports, and means for detachably securing said steam-chest to the steam-cylinder.

13. A steam-chest for locomotives and the like, comprising a casting provided with a valve-chamber extending longitudinally therethrough, a steam-inlet arranged intermediate of the ends of the casting, induction and eduction steam passages arranged on both sides of the steam-inlet, said passages terminating at the bottom of the casting, lubricant-receiving openings arranged

- adjacent the steam-inlet, exhaust passages arranged in the side walls of the casting so as to substantially encircle the valve-chamber, said exhaust passages communicating with the ends of the valve-chamber and terminating in a central downwardly presented exhaust port arranged intermediate of the induction and eduction ports, all of said ports being arranged to register with the ports in the flat valve face of a slide-valve type cylinder. 5
14. A steam-chest for locomotives and the like, comprising a casting provided with a valve-chamber extending longitudinally therethrough, a steam-inlet arranged centrally between the ends of the valve-chamber, circumferential steam-channels formed on the inner periphery of the casting on opposite sides of said steam-inlet, bushings 15 provided with ports arranged in the valve chamber intermediate of the steam-inlet and the ends of said chamber, means whereby the ports of the bushings are brought to register with said circumferential channels, induction and eduction ports arranged in the bottom of the casting and in communication with said channels, exhaust passages arranged in the side walls of the casting and communicating with both ends of the valve-chamber, said exhaust passages extending to a central point of the casting and terminating in a single port extending through the bottom of the casting intermediate of the induction and eduction ports, in combination with an inside admission piston-valve arranged to confine the live steam intermediate of the ends thereof, said piston-valve being arranged to establish communication through its interior for the exhaust 20 steam. 40
15. In combination with a slide-valve type cylinder, a steam-chest provided with a steam-inlet intermediate of its ends, steam-channels arranged on opposite sides of said inlet and terminating in induction and eduction ports adapted to register with the induction and eduction ports of the cylinder, exhaust passages arranged in the walls of the steam-chest and communicating with both ends of the chest, said exhaust passages communicating at a central point and terminating in an exhaust port intermediate of the induction and eduction ports 45 50 55 60 65 70 75 80 85 90 95 100
- and adapted to register with the exhaust port of the cylinder, and means for detachably securing the steam-chest to the valve face of the cylinder. 16. A steam-chest for locomotives and the like, comprising a casting having a flat faced bottom, provided with a valve-chamber extending longitudinally therethrough, a steam-inlet communicating at a central point with the valve-chamber, circumferential steam-channels arranged on the inner periphery of the casting on each side of said steam-inlet, induction and eduction ports arranged in the bottom of said casting and communicating with said channels, said ports terminating in the flat face of the casting, segmental exhaust steam passages arranged in the side walls of the casting and extending from end to end, said passages having communication with both ends of the valve-chamber and terminating at a central point in a downwardly presented exhaust port, means for injecting lubricant adjacent the steam-inlet point of the valve-chamber, and means for detachably securing the steam-chest on the flat valve face of a slide-valve type cylinder. 17. A steam-chest for locomotives and the like, comprising an integral casting having a flat faced bottom provided with induction and eduction ports and an exhaust port arranged to communicate with the ports of a slide-valve type of cylinder, said casting being provided with a steam inlet, and with steam passages communicating with the ends of the chest interior and extending throughout the side walls thereof, said last mentioned passages terminating in a single downwardly presented passage communicating with the exhaust port in the bottom face of the casting, in combination with a piston valve comprising a hollow open ended cylindrical portion adapted to confine the live steam intermediate of the ends of said cylindrical portion and the inner walls of the steam-chest while the exhaust steam has free passage through said cylindrical portion of the valve from end to end of the steam-chest. 100
